UNITED STATES PATENT OFFICE.

REMIGIUS D'ANTONIO, OF CAPISTRANO, AQUILA, ITALY.

REFLECTOR FOR WIRELESS TELEGRAPHY.

986,806.

Specification of Letters Patent. Patented Mar. 14, 1911.

Application filed January 27, 1910. Serial No. 540,355.

To all whom it may concern.

Be it known that I, REMIGIUS D'ANTONIO, a subject of the King of Italy, residing at Capistrano, Aquila, Abruzzi, Italy, have invented certain new and useful Improvements in Reflectors for Wireless Telegraphy, of which the following is a specification.

This invention relates generally to wireless telegraphy, and particularly to a system designed to be employed by vessels to prevent collisions in foggy or heavy weather.

The present invention embodies in its conception the well-known Marconi system of wireless telegraphy, in all its details, and therefore requires no detailed description of its application.

The object of the present invention is so to mount the reflectors, that they will always maintain a horizontal plane irrespective of the angle of the deck of the vessel, thus to insure the reflection of signals from a vessel within the wave lines.

With the above and other objects in view, as will appear as the nature of the invention is better understood, the same consists, broadly stated, in a signaling device for vessels embodying in its construction a Marconi system of wireless telegraphy, including a counterbalanced reflector, the mounting of which will be such as to maintain it in stable equilibrium irrespective of the angle assumed by the deck of the vessel.

The invention consists further in the various novel details of construction of a reflector for use in connection with a wireless telegraph system, as will be hereinafter fully described and claimed.

In the accompanying drawings, forming a part of this specification, and in which like characters of reference indicate corresponding parts: Figure 1 is a view, in the nature of a diagram, displaying the system as applied to a vessel. Fig. 2 is a view in side elevation of the reflector. Fig. 3 is a view similar to Fig. 2, but showing the parts of the reflector equilibrator separated. Fig. 4 is a view in rear elevation, partly in section, of the reflector support.

In installing the invention, two reflectors 1 and 2 are employed, which, as shown in Figs. 2 and 3, are semicircular in cross-section, although the ordinary form of paraboliform reflector may be substituted, if preferred, or found of advantage. These reflectors are placed on the bridge of the vessel, one to starboard and the other to

port, and the reflector 2 projects in a forward direction, the electric waves produced by the oscillator 3, and the reflector 1, if it is in the line of the waves from the reflector 2, are directed to the coherer 4. Under these conditions, the coherer establishes a circuit with the battery 5, in which circuit is comprised a relay 6, the object of which is to complete the other circuit with the battery 7. In the circuit of the battery 7 is included a bell 8 and a de-cohering tapper 9 of the usual or any preferred construction.

The above description is general in character, and refers, as above stated, to the Marconi system.

Under existing conditions, the reflectors of a Marconi system on shipboard are practically limited to atmospheric conditions—that is to say if the weather be stormy the reflectors, owing to an absence of any means for maintaining them in a plane parallel with the horizon is absent. As will be obvious, to secure effective results, it is necessary that whatever may be the conditions of the weather, the reflectors should maintain a condition of stable equilibrium, irrespective of climatic conditions, thus to insure the positive coaction between the two reflectors. The reflectors may be of semi-spherical form or of paraboliform and may be of any material adapted to the purpose.

The apparatus comprises two semi-spherical bearings 10 that are designed to encircle partially a ball 11 carried by the shank 12 of the reflector 13 with which is combined the coherer 4 of the usual or any preferred construction. The bearings 10 are counterparts, and each is provided with an elongated portion 14 arranged to fit within a socket 15 in the upper end of a base 16, the lower ends of which are substantially bolted to a base 17. The members of the bearings 10 are held assembled by a bolt 18, a nut 19 serving to hold the parts properly assembled.

In operation, the counterpoise 20 will serve to maintain the focal axis of the reflector parallel with the horizon irrespective of the coherer, and by the provision of the bolt 18 and nut 19, the response of the reflector to the undulations of wave motions will be delicately responsive to all conditions.

In Fig. 1 of the drawings, the transmitter and receiver, installed on a ship, are shown in combination. In the part of the appa-

tus comprising the transmitter there are three electric circuits. The first is formed between the battery 7 and the motor 22, and is closed by lowering the key 25'. The second circuit is derived from the points A and B and comprises the primary P of induction coil 21. This latter circuit is closed alternately by the eccentric 23, fixed to the shaft of the motor 22 as the eccentric presses against the contact 24 and causes it to engage the binding post 25. The third electric circuit is derived from the first at M and the second at N. This third circuit includes the signal bell 8 and the decohering tapper 9, and is dependent for its closing upon the relay 6. In the part of the apparatus comprising the receiver there is only one electric circuit, which includes the battery 5, the coherer 4 and the relay 6. The electric circuits being thus described, the functions of the transmitter and receiver will readily be understood. As regards the former when the key 25' is lowered, a circuit is established between the battery 7 and the motor 22, and the latter is thereby caused to operate. Each time the contact 24 comes into engagement with the binding post 25, the current passes to the primary P of the induction coil 21 and thence to the spark gap 3 placed in the focus of the reflector 2, whereupon the electric sparks are generated, which produce the electric waves that are projected forward by the reflector. As regards the receiver, when the electric waves projected forward by the reflector of an-

other ship fall upon the reflector 1, the coherer 4 is energized, and thus the circuit of the battery 5 being closed the relay 6, the signal bell 8 and the decohering tapper 9 are put in action.

It may be noted that in accordance with the present invention, the reflectors 1 and 2 are situated on the bridge of the ship, one to the right and the other to the left.

The signaling action of the present invention is possible only when the apparatus as described is installed on two vessels that threaten to collide. In this way, waves are projected directly from the transmitter of one ship to the receiver of the other and there is thus a mutual interchange of signals.

I claim:

A wireless signaling system for vessels embodying spaced supports at different points upon the vessel, a slotted bearing socket upon each support, a ball journaled in each socket, a stem carried by each ball and projecting through and movable in the slots in each socket, a reflector upon one end of each stem, a counterbalancing weight upon the opposite end of each stem, and wireless signaling means including a transmitter associated with one reflector and a receiver associated with the other reflector.

In testimony whereof I affix my signature in presence of two witnesses.

REMIGIUS D'ANTONIO.
